United States Patent Office

Des. 196,452
Patented Oct. 1, 1963

196,452

COMBINED MAGNIFIER AND HOLDER

James N. Burlin, New York, N.Y., and Henry Dreyfuss,
South Pasadena, Calif., assignors to Bausch & Lomb
Incorporated, Rochester, N.Y., a corporation of New
York

Filed June 13, 1962, Ser. No. 70,527

Term of patent 14 years

(Cl. D57—1)

FIG. 3

FIG. 5

FIG. 4

FIG. 1

FIG. 2

FIG. 1 is a top perspective view in open condition of a combined magnifier and holder embodying our new design;

FIG. 2 is a bottom perspective view thereof;

FIG. 3 is a top plan view thereof in closed condition;

FIG. 4 is an end elevational view thereof; and

FIG. 5 is a side elevational view thereof in open condition.

We claim:

The ornamental design for a combined magnifier and holder, substantially as shown and described.
